UNITED STATES PATENT OFFICE.

JAMES F. McELROY, OF ALBANY, NEW YORK; SUSIE H. McELROY, EXECUTRIX OF SAID JAMES F. McELROY, DECEASED, ASSIGNOR TO CONSOLIDATED CAR-HEATING COMPANY, A CORPORATION OF WEST VIRGINIA.

ELECTROMAGNET.

1,149,275.

Specification of Letters Patent. Patented Aug. 10, 1915.

Application filed March 7, 1911. Serial No. 612,810.

To all whom it may concern:

Be it known that I, JAMES F. McELROY, a citizen of the United States, residing at Albany, county of Albany, State of New York, 5 have invented certain new and useful Improvements in Electromagnets, the following being a full, clear, and exact disclosure of the one form of my invention which I at present deem preferable.

10 For a detailed description of the present form of my invention, reference may be had to the following specification and to the accompanying drawings, which illustrate my invention.

15 Figure 1 is a plan partly in section, Fig. 2 is a front elevation, Fig. 3 is a transverse section through the center of the valve, Figs. 4 and 5 are sections through the valve disks, Fig. 6 is a diagram of the electric circuit.

20 This invention is an electromagnetic operating mechanism particularly intended for pneumatic service. It comprises in general two operating solenoids facing each other, 25 but separated a slight distance apart and having a common magnetic core which passes across the separating space and, as it is moved to and fro by the attraction of one solenoid to another, it operates a lever on 30 the shaft of the valve. In the said separating space between the opposed faces of the solenoid and at the bottom of said space is a junction box for the electric wires.

25 Turning to the accompanying drawing, 35 the standard of the device is formed by a casting containing the aforesaid junction box A (shown in section in Fig. 3) and two hollow solenoid end-plates A¹, A² extending upward from either side of the junction box 40 A, as appears in Fig. 2, and forming the inner opposed ends of the two solenoids. This casting will be of iron or other magnetic material. Into the rear of each of the 45 end plates A¹ and A² are screwed thimble-shaped iron caps B¹ and B² which inclose the respective solenoids. The two solenoids have a common magnetic core or plunger B which is adapted to move to and fro in the hollow centers of the exciting solenoid coils 50 D¹ and D², and also to pass across the space separating the end plates A¹ and A². The coils D¹ and D² are wound in the usual manner upon hollow forms or spools, and in this case the central bores or openings of the

spools are enlarged at each end to receive 55 tubular projections B³ formed on each of the caps B¹ and B² and similar tubular extensions A³ formed on the end pieces A¹ and A². By this means the exciting coils surround not only the plunger B but also the 60 magnetic tubular portions B³ and A³ of the external magnetic casing. This adds materially to the power of the solenoids. Each of the end caps B¹ and B² has its central opening closed by a screw plug b carrying 65 leather end pad b¹. By this means the throw of the plunger B may be readily adjusted with respect to the alinement of the ports in the valve which the plunger B operates. Near the center of the plunger B is fixed a 70 surrounding ring C with a horizontal fork on its upper side (see Fig. 3) embracing the extremity of the valve lever E. The said lever is slotted at its extremity and a pin C¹ passing through the fork on the ring C 75 enters the said slot and serves to operate the lever E as the plunger B moves from side to side. On the said ring C is a projecting handle C² by which the plunger may be operated manually in the event of a failure 80 of the electric current that energizes the solenoids. A brake-shoe c operated by a spring c² and pivoted by the spindle c¹ serves to deaden the movement of the plunger B. It has happened in the use of 85 electro-pneumatic valves of this kind for controlling the doors of railway cars that the jarring of the train would cause the plunger to work forward and operate the valve of the pneumatic motor to cause the 90 opening of the door. This is prevented by the brake shoe c, although the pressure applied thereto by the spring c² is not sufficient to interfere with the normal operation of the plunger by the solenoids. The valve 95 itself is mounted on a bracket at one side of the aforesaid space between the facing ends of the solenoids. The valve structure comprises a base block F traversed by the four air ducts 1, 2, 3 and 4 of which 1 and 2 enter horizontally on the opposite sides while 3 and 4 enter vertically from the bottom. These four ducts terminate (see Figs. 4 and 5) in ports, numbered correspondingly 1, 2, 3 and 4, on the horizontal valve seat formed 100 on the upper side of the block F. There are also supplementary ports 1^a and 2^a for the ducts 1 and 2 respectively as particularly 105

appears in Figs. 4 and 5. On the valve seat aforesaid rests the valve-disk G which is pressed down upon the seat by the spring F² (see Fig. 3), which, at its lower end, rests 5 in a circular recess in the top of the valve-disk G. Its upper end rests in a recess formed on the under side of a plate F³ on the upper side of which is a small semi-circular lug bearing on the inner surface of 10 the cap F¹. By this means the spring F² is free to rotate with the valve-disk G which tends to ease the movement of the disk. The said valve-disk G is provided on its 15 under side with a hub g which enters a cylindrical recess on the upper side of the block F. This hub g has on its under side a diametrical slot or groove in which engages a tongue on the upper end of the spindle K. The spindle K passes vertically through a 20 central opening in the block F and carries at its lower end the aforesaid valve lever E. This construction is one which affords ready and convenient access to the valve and also renders it easy to assemble and take apart. 25 Thus by simply unscrewing the cap piece F³ the valve disk G and its seat are exposed and the valve may be operated while it is thus exposed either manually or by the solenoids. While it is thus exposed, its correct operating 30 positions being indicated by external marks, the adjusting plugs b of the solenoid may be screwed in or out until the throw of the plunger B from one side to the other will rotate the valve-disk the exact distance required to move it from one operative position to another. Conversely, in assembling, 35 the spindle K will be dropped through the opening in the block F and its lower end secured to the lever E. Then the valve disk G will be placed on its seat and turned until the groove in its hub g fits over the tongue on the spindle K. Then the spring F² is placed on the valve disk and the cap F¹ screwed down in place. The valve-disk G is traversed by suitable ducts for establishing 40 the desired connections between the aforesaid ports on the valve seat. These ducts in the disk G are shown in Figs. 4 and 5 as forming two T-shaped passages, the 45 extremities of which lie in the circular line occupied by the aforesaid ports. Thus in the position of the valve disk shown in Fig. 4 the ducts in the disk serve to connect port 1 with port 3 and port 2 with port 4, and, if the port 1 is in communication with the 50 source of air supply and port 2 with the exhaust, the effect will be to connect the motor-port 3 with the source of supply and the motor-port 4 with the exhaust. Conversely, with the opposite position of the 55 valve disk, shown in Fig. 5, the supplementary port 1^a is in communication with the motor-port 4 and the supplementary port 2^a with motor-port 3. This will give the 60 reverse operation, remembering that ports 1 65

and 1^a are both in communication with the same admission duct and the ports 2 and 2^a with the same outlet duct. By this arrangement of supplementary ducts a comparatively short range of rotation of the disk G is required. I call particular attention to the fact that in this valve no stuffing-boxes are required, since the spindle K by which the disk G is operated passes through the seat on which the disk rests, both the inlet and outlet ports in the seat being covered by the disk.

The junction box A heretofore mentioned is provided, as shown in Fig. 3, with openings on opposite sides into which may be screwed pipes containing the electric wires and from its junction box connection can be made with the wires leading into the respective solenoids, the box having a removable cover a.

Turning to Fig. 6, S¹ and S² represent switches of any suitable kind normally held in the open position by springs, but adapted to be turned to one side or the other for the operation of either the solenoid D¹ or the solenoid D². The source of current is represented by the battery L, the left hand terminal of which is connected with the lever of each switch S¹ and S². The other terminal of the battery is connected to the inner terminals of both solenoids D¹ and D². The outer terminal of the solenoid D¹ is connected to the outer terminal of each switch, and the outer terminal of the solenoid D² is similarly connected to the inner terminals of both switches. Hence by turning the switch S¹ to the left the solenoid D¹ will be energized and by turning it to the right the opposite solenoid D². Similarly by turning the switch S² to the left the solenoid D² will be energized and by turning it to the right the solenoid D¹.

What I claim as new and desire to secure by Letters Patent is:

1. An electro-magnetic operating mechanism comprising a junction box, and spaced apart end plates extending from either side of said junction box in a single unitary structure, oppositely disposed solenoid coils, said end plates having means for supporting the inner ends of the respective coils, a reciprocatory core coacting with said coils, and an operating member connected to said core.

2. An electro-magnetic operating mechanism comprising a junction box and spaced apart end plates extending from either side of said junction box in a single unitary structure, said end plates having flanges oppositely disposed magnetic casings supported at their inner ends by said flanges, coils located within said casings, a reciprocatory core coacting with said coils, and an operating member connected with said core.

3. An electro-magnetic operating mechanism comprising a junction box and spaced apart end plates extending upwardly from either side of said junction box in a single unitary structure, oppositely disposed magnetic casings having their inner ends removably attached to said end plates, coils located within said casings, a reciprocatory core coacting with said coils and spanning the space between said end plates above said junction box, and an operating member connected with said coil. 70
4. An electro-magnetic operating mechanism comprising a standard having spaced apart end plates, oppositely disposed magnetic caps having their inner ends attached to and supported by said end plates, the outer ends being free of and extended away from said standard, solenoid coils within said caps, a reciprocatory core cooperating with said coils, and an operating member connected with said core. 75
5. An electro-magnetic operating mechanism comprising a standard having spaced apart end plates, oppositely disposed magnetic caps having their inner ends attached to and supported by said end plates, the outer ends being free of and extended away from said standard, solenoid coils within said caps, a reciprocatory core cooperating with said coils, an operating member connected with said core, and means carried by said caps for adjusting the throw of said core. 80
6. An electro-magnetic operating mechanism comprising a standard having spaced apart end plates, oppositely disposed magnetic caps having their inner ends attached to and supported by said end plates, the outer ends being free of and extended away from said standard, solenoid coils within said caps, a reciprocatory core cooperating with said coils, and an operating member connected with said core, said end plates being provided with outwardly projecting tubular extensions engaging the inner ends of the respective solenoid coils. 85
7. An electro-magnetic operating mechanism comprising a standard having spaced apart end plates, oppositely disposed magnetic caps having their inner ends attached to and supported by said end plates, the outer ends being free of and extended away from said standard, solenoid coils within said caps, a reciprocatory core cooperating with said coils, and an operating member connected with said core, said caps being provided with tubular extensions engaging the outer ends of the respective solenoid coils. 90
8. An electro-magnetic operating mechanism comprising a standard having spaced apart end plates, oppositely disposed magnetic caps having their inner ends supported by said end plates, the outer ends being free, solenoid coils within said caps, a core cooperating with said coils, and an operating member actuated by said core. 95
9. An electro-magnetic operating mechanism comprising a standard having spaced apart end plates, oppositely disposed magnetic caps having their inner ends supported by said end plates, the outer ends being free, solenoid coils within said caps, a core cooperating with said coils, an operating member connected with said core, and means connected with the core between said end plates to manually operate the core in the event of failure of the solenoid current. 100
10. An electro-magnetic operating mechanism comprising a standard having spaced apart end plates, oppositely disposed magnetic caps having their inner ends supported by said end plates, the outer ends being free, solenoid coils within said caps, a core cooperating with said coils, a ring secured to said core, an operating member connected with said ring, and an actuating handle also connected to said ring. 105
11. An electro-magnetic operating mechanism comprising a standard having spaced apart end plates, oppositely disposed magnetic caps having their inner ends supported by said end plates, the outer ends being free, solenoid coils within said caps, a core cooperating with said coils, a ring secured to said core between said end plates and provided with a fork, and an operating member connected with said fork. 110
12. An electro-magnetic operating mechanism comprising a standard having spaced apart end plates, oppositely disposed magnetic caps having their inner ends supported by said end plates, the outer ends being free, solenoid coils within said caps, a core cooperating with said coils, a ring secured to said core between said end plates and provided with a fork, an operating member connected with said fork, and an actuating handle also connected to said ring. 115
13. An electro-magnetic operating mechanism comprising a standard provided with an end plate, a cylindrical cap having its open end in detachable engagement with said end plate, the closed end of said cap being free of and extended away from said end plate, a solenoid coil inclosed by said cap, a solenoid core, and an operating member actuated by said core. 120
14. An electromagnetic operating mechanism comprising a standard provided with an end plate, a cylindrical cap supported at one end by said end plate, the closed end of said cap being free, a solenoid coil inclosed by said cap, a solenoid core, an operating member actuated by said core, and an ad- 125
- 65 free, solenoid coils within said caps, a core 130

justing plug entering said cap, said end plate being provided with a tubular projection inclosed by said coil.

15. An electro-magnetic operating mechanism comprising a standard having spaced apart end plates provided with outwardly extended flanges, oppositely disposed magnetic caps having their inner ends removably attached to said flanges, solenoid coils 10 inclosed by said caps and flanges, a core co-

operating with said coils, and an operating member actuated by said core.

In witness whereof I have hereunto set my hand, before two subscribing witnesses, this fourth day of March, 1911.

JAMES F. McELROY.
